UNITED STATES PATENT OFFICE.

CLINTON M. SEARL, OF PORTSMOUTH, OHIO, ASSIGNOR TO THE VULCAN LAST COMPANY, OF PORTSMOUTH, OHIO, A CORPORATION OF OHIO.

LAST.

Application filed April 14, 1922. Serial No. 552,612.

To all whom it may concern:

Be it known that I, CLINTON M. SEARL, a citizen of the United States, and a resident of Portsmouth, county of Scioto, State of

5 Ohio, have invented certain new and useful Improvements in Lasts, of which the following is a specification.

10 My invention relates to an improvement in lasts of the type which are divided transversely into a toe part and a heel part, and an object thereof is to so construct the last that the same will be held either in collapsed position or extended position as the case may be.

15 A further object of my invention is the provision of a joint between the two parts of the last which will prevent vertical displacement of the last parts when the last is extended but which will permit of movement of the last parts to collapsed position when so desired.

20 A further object of my invention is the provision of an improved form of link connecting the last parts, displacement of one 25 end of the link relatively to one last part being prevented by a pair of pins, while displacement of the other end of the link with respect to the other last part is prevented by a single pin. These pins are so 30 positioned relatively to each other and to the fulcrum of the last parts that a line drawn through the center of the pin in one last part and the center of one of the pins in the other last part will fall below the fulcrum of the last parts when the last is extended, while a line drawn through the center of the one pin in one last part and the center of the other pin in the other last part will fall above this fulcrum when the last 35 is collapsed.

40 In the accompanying drawing I have illustrated a last in extended position with a portion broken away to show the construction of the joint between the two last parts 45 and that of the connecting link and to illustrate the relative location of the pins by which displacement of the link is prevented.

45 My improved last is divided transversely into a toe part 1 and a heel part 2 along the 50 substantially vertically extending line 3 and substantially horizontally extending line 4, a V-cut 5 the bottom of which extends to the point or fulcrum 6 being provided in the

upper part of the last so as to permit of relative movement of the two last parts from 55 extended to collapsed position.

It will be seen therefore that the heel part 2 may be said to be provided with a rectangular groove, the lines 3 and 4 constituting the two sides of this groove. The toe part 60 on the other hand is provided with a rectangular projection 7 complementary to the rectangular groove in the heel part, this projection fitting into the groove in the heel part when the last parts are extended to effectively prevent vertical displacement of the last parts. When the last parts are moved to collapsed position they pivot about the edge 6 of the groove as a fulcrum, the projection 7 on the toe part moving out of 70 the rectangular groove in the heel part.

The toe part 1 is provided with a vertically extending recess 8 and the heel part is provided with a similar recess 9, these recesses being provided for the reception of a 75 link 10. This link is in the form of a flat metal member bent back upon itself about a spring pin 11 extending transversely of the heel part 2, this pin preventing displacement of the looped end of the link relatively 80 to the heel part. The other ends of this link extend into the recess 8 in the toe part and are provided with bent over portions or projections 12 and 13. The bent over portion 12 receives or is bent around a spring pin 14 85 in the toe part while the projection 13 receives or is bent around a spring pin 15 also in the toe part so that the end of the link received by the toe part is held against displacement by the pins 14 and 15. 90

The pins 14 and 15 are so located with respect to the pin 11 that the pin 14 will cooperate with the projection or turned over portion 12 of the link when the last is extended while the pin 15 will cooperate with 95 the projection or turned over portion 13 when the last parts are collapsed. In order that the last parts may be held either in collapsed or extended position as the case may be the spring pin 14 is so located with 100 respect to the spring pin 11 that a line passing through the centers of these pins will fall below the edge 6 of the rectangular groove in the heel part when the last is extended, the pin 14 at this time as above 105 pointed out cooperating with the projection

12 to thereby hold the last extended. The spring pin 15 is so located with respect to the pin 11 that a line passing through the centers of these pins will fall above the edge 6 of the rectangular groove when the last parts are collapsed, the pin 15 at this time cooperating with the projection or turned over portion 13 to thereby hold the last collapsed.

10 The pins 11, 14 and 15 being of resilient material such as spring steel, will permit the last parts to be moved from extended to collapsed position and vice versa, these pins yielding as the last parts pass from one position to the other and thereafter holding the parts in adjusted position.

15 While I have described a specific embodiment of my invention it is to be understood that changes may be made in the details of 20 construction here illustrated and described within the purview of my invention.

I claim:

1. A last divided transversely into a toe part and a heel part, a link, a pin for preventing displacement of one end of said link with respect to one last part, projections on the opposite end of said link, and a pair of pins cooperating with said projections for preventing displacement of this 30 end of the link, one of said pair of pins cooperating with one projection when the last is extended and the other pin cooperating with the other projection when the last is collapsed.

35 2. A last divided transversely into a toe part and a heel part, a link, a spring pin by which displacement of one end of said link is prevented, projections on the opposite end of said link, and a pair of spring pins for preventing displacement of this end 40 of the link, a pin of said pair cooperating with one projection when the last is extended and the other pin of said pair cooperating with the other projection when the last is collapsed.

45 3. A last divided transversely into a toe part and a heel part, a link, a spring pin for preventing displacement of one end of said link with respect to one last part, projections on the opposite end of said link and a pair of spring pins for preventing displacement of this end of the link, one of 50 said pair of pins cooperating with one of the projections on the said link when the last is extended and so located with respect to the pin at the other end of the link that a line passing through the centers of said pins falls below the pivotal point of the last parts when the last parts are in extended 55 position, the other pin of said pair cooperating with the other projection on said link when the last parts are collapsed and being so located with respect to the pin at the other end of the link that a line passing 60 through the centers of said last-mentioned

pins will fall above the pivotal point of the last parts when the last parts are in collapsed position.

4. A last divided transversely into a toe part and a heel part, a pin carried by the heel part, a link bent around said pin and having its two ends extending into a recess in the toe part of the last, a pair of pins carried by the toe part of the last and about which the forward ends of the link are bent so that the forward ends of the link are held by said pins against displacement, one of said pins in the toe part being so positioned with respect to the pin in the heel part that a line passing through the centers 70 of said pins will fall below the fulcrum of the last parts when the last parts are in extended position, the other pin in the toe part of the last being so located with respect to the pin in the heel part that a line passing through the centers of these last-mentioned pins will fall above this fulcrum when the last parts are in collapsed position.

5. A last divided transversely into a toe part and a heel part, one of said last parts being provided with a substantially rectangular groove, the other of said parts being provided with a complementary projection extending into said groove, a link, a pin in one part of the last for preventing displacement of one end of the link, pins in the other part of the last for preventing displacement of the opposite end of the link, said pins being so located that a line passing through the centers of one of the pins in the toe part of the last and the pin in the heel part of the last will fall below the edge of said rectangular groove when the last parts are in extended position and so that a line drawn through the center of the other pin in the toe part and the pin in the heel part will fall above the edge of said groove when the last parts are in collapsed position.

6. A last divided transversely into a heel part and a toe part, one of said last parts being provided with a rectangular groove, the other last part being provided with a complementary projection extending into said groove, a link, a spring pin for preventing displacement of one end of said link with respect to one last part and a pair of spring pins for preventing displacement of the other end of said link with respect to the other last part, one pin of said pair being so located with respect to the spring pin in the other last part that a line passing through the centers of said pins will fall below one edge of the rectangular groove when the last parts are extended, the other spring pin of said pair being so located with respect to the spring pin at the opposite end of the link that when the last parts are collapsed a line passing through the centers of said 110

last-mentioned pins will fall above said edge of the rectangular groove.

7. A last divided transversely into a toe part and a heel part, the heel part being provided with a rectangular groove, the edge of which together with a portion of the face of the toe part constituting a bearing about which the last parts are movable, a complementary projection in the toe part 10 extending into said groove, a link, a pin for preventing displacement of one end of said link with respect to the heel part of the last, pins for preventing displacement of the other end of said link with respect to the 15 toe part of the last, said pins being so located that when the last parts are moved to collapsed position the projection on the

toe part will disengage the recess in the heel part and a line passing through the centers of one of the pins in the toe part 20 and the pin in the heel part will fall above the edge of said rectangular groove, a line drawn through the centers of the other pin in the toe part and the pin in the heel part falling below the edge of said groove when 25 the last parts are extended, the projections on the toe part with the last so extended projecting into the groove in the heel part to prevent relative vertical movement of the two last parts. 30

This specification signed this 10 day of April, 1922.

CLINTON M. SEARL.
